(57) **CLAIM**

The ornamental design for a shoe sole, as shown and described.

DESCRIPTION

FIG. 1 is a left side view of a shoe sole in accordance with our new design;

FIG. 2 is a right side view thereof;

FIG. 3 is a front view thereof;

FIG. 4 is a rear view thereof;

FIG. 5 is a top view thereof;

FIG. 6 is a bottom view thereof;

FIG. 7 is a perspective view showing a left side face, a top face and a rear face thereof;

FIG. 8 is a perspective view showing a right side face, a top face and a rear face thereof;

FIG. 9 is an enlarged end view taken along line 9-9 of FIG. 6;

FIG. 10 is an enlarged end view taken along line 10-10 of FIG. 6;

FIG. 11 is an enlarged end view taken along line 11-11 of FIG. 6;

FIG. 12 is an enlarged view of the portion of the shoe sole shown within the area designated as 12 in FIG. 9;

FIG. 13 is an enlarged view of the portion of the shoe sole shown within the area designated as 13 in FIG. 10; and,

FIG. 14 is an enlarged view of the portion of the shoe sole shown within the area designated as 14 in FIG. 11.

The small dashed broken lines in the figures depict portions of the shoe sole that form no part of the claimed design. The larger dashed broken lines in the sectional views indicate surfaces that form no part of the claim. The peripheral dash dot dash broken lines in FIGS. 9-14 illustrate the cut line of the enlarged sectional views and form no part of the claim.

1 Claim, 12 Drawing Sheets
